CLAIM

We claim the ornamental design for a data capture device, as shown and described.

DESCRIPTION

FIG. 1 is a first perspective view of a data capture device; FIG. 2 is a second perspective view thereof; FIG. 3 is a front side view thereof; FIG. 4 is a rear side view thereof; FIG. 5 is a right side view thereof; FIG. 6 is a left side view thereof; FIG. 7 is a top side view thereof; and, FIG. 8 is a bottom side view thereof.

Broken lines seen in the drawings depict portions of the data capture device that form no part of the claimed design.

1 Claim, 8 Drawing Sheets
